UNITED STATES PATENT OFFICE.

WILLIAM T. BELL, OF NEW YORK, N. Y.

STEAM ROCK-DRILL.

SPECIFICATION forming part of Letters Patent No. 258,974, dated June 6, 1882.

Application filed February 13, 1882. (No model.)

To all whom it may concern:

Be it known that I, WILLIAM T. BELL, of the city, county, and State of New York, have invented certain new and useful Improvements 5 in Steam Rock-Drills, which are hereinafter fully and clearly described, reference being made to the annexed drawings, which form a part of this specification.

My improvements are applicable especially 10 to rock-drills where rotary and vertical motions are required at the same time; but my invention may also be applied successfully to steam-pumps and other steam-cylinders.

The object of my invention is to dispense 15 with valves and ratchets in rock-drills and the heavy, expensive, and cumbrous machinery necessary to operate them.

In all kinds of rock-drills two concurrent 20 motions of the drill are necessary to effectually produce the desired result—namely, a rotary and a vertical motion. The vertical motion in rock-drills has heretofore been obtained by an ordinary piston and valves operated by machinery. The rotary motion has been obtained by means of ratchets operated by 25 machinery. This principle of constructing and operating rock-drills has been found to be cumbersome, awkward, expensive, and easily disarranged.

30 In my improved rock-drill, hereinafter described, the necessary vertical and rotary motions are secured by means of a curiously-constructed cylinder and piston, shown in the drawings, as follows:

35 Similar letters indicate similar parts.

Figure 1 is a longitudinal sectional view of the cylinder-piston. Fig. 2 is a transverse section of the cylinder, piston, and steamways. Fig. 3 is a plan view of the irregular grooves 40 in the upper chamber of the cylinder. Fig. 4 is a plan view of the piston with its steam and exhaust ways. Fig. 5 is a transverse sectional view of the same. Fig. 6 is a transverse section of the cylinder and the supply and exhaust pipes.

45 On the upper end of the piston A there are constructed and attached two or more studs, c c, set opposite each other, and made in the form of an ellipse. These two studs operate in the vertical irregular grooves d d d and a a a

inside the cylinder. When the piston carrying the drill B ascends the studs ascend in the grooves a a a, and when the piston descends the studs descend in the grooves d d d, thus carrying the drill round a given distance at 55 each stroke of the piston, and effecting without any ratchet or other machinery the necessary and perfect rotary motion of the drill.

The piston which operates in the steam-cylinder C is provided with grooves g g' g g², as 60 shown in Figs. 4 and 5. As the piston ascends it makes a partial revolution, as above explained, which brings the two uppermost steamways or grooves, g' g', directly opposite the holes f f' in the steam-cylinder, where the steam 65 is admitted and the piston forced downward, when it makes another partial revolution, which carries these same steamways round directly opposite the holes s s in the cylinder, where the steam is exhausted. Again, when 70 the piston is forced downward and makes a partial revolution, as explained, the grooves g' g² are brought directly opposite the holes f f' in the steam-cylinder, where the steam is admitted and the piston forced upward to the 75 point where the steam is exhausted, as before explained. Thus it will be seen that valves are entirely dispensed with, and that the piston is constructed and made to operate in such a manner as to form of itself an automatic 80 valve or valves.

The piston and cylinder of this rock-drill are so constructed and arranged that in and of themselves they produce all the motions essential in a perfect rock-drill.

Having thus described my invention, what I claim and desire to secure is—

A rock-drill composed of a piston having two or more elliptical studs adjusted to the upper end thereof, and having a series of 90 straight grooves or steamways at each end thereof, a series of connected irregular grooves in which the elliptical studs attached to the piston operate to produce a rotary motion at each stroke of the piston, substantially as described. 95

WILLIAM T. BELL.
